UNITED STATES PATENT OFFICE

HERBERT L. CHAPIN, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY

ABRADING MACHINE

Application filed February 11, 1929. Serial No. 339,179.

This invention relates to abrading machines and is herein illustrated as embodied in a machine for scouring the heels of boots and shoes. In machines of this class the 5 edge of the heel of a shoe is presented to the periphery of a scouring wheel, and as the material of the heel is thus abraded, dust is driven off in a direction approximately tangential to the wheel. It has been customary to provide a conduit in communication with a suction draft system to receive and carry away some of the dust thus given off by the work. The fact that the toe portion 10 of the shoe extends in the direction of the dust stream given off by the work in certain positions thereof presents a serious difficulty in the design of the receiving end of such a conduit, and has prevented hitherto the design of a receiving end which not only 15 gathers in all of the dust but also permits the fullest degree of manipulation of the shoe without interference with the toe portion thereof.

One of the objects of this invention is 20 to provide a dust receiving member which will be free from the difficulty above described. In accordance with this object a portion of the illustrated dust collecting member is in the form of a funnel having 25 a large open end adjacent to the periphery of a scouring wheel to receive dust given off from the work, another portion of the dust collecting member being, as illustrated, in the form of an open-bottomed V-shaped 30 trough lying in the plane of the scouring wheel to receive additional dust and opening at one end into the funnel. The other end of the illustrated trough is closed and at a lower level, and the remaining portion 35 of the dust collecting member shown in the drawings is in the form of a conduit providing communication between the intake 40 of a suction draft system on the one hand and the small end of the funnel and the bottom of the trough on the other hand. The illustrated dust collecting member, by 45 reason of its shape as above described, is enabled not only to gather substantially all of the dust given off by the work but also 50 to distribute the intensity of the draft pass-

ing through it in such a manner as to avoid deposits of entrained dust, while at the same time the dust collecting member is enabled to avoid interference with the shoe, and particularly with the toe end of the shoe, as 55 the edge of the heel of the shoe is presented to the scouring wheel.

These and other features of the invention will be described as embodied in an illustrative machine and pointed out in the appended claims.

Referring now to the accompanying drawings,

Fig. 1 is a front elevational view of a machine which embodies the invention; 65

Fig. 2 is a side elevational view of the machine shown in Fig. 1;

Fig. 3 is a sectional view taken on the line III-III of Fig. 1;

Fig. 4 is an enlarged fragmentary view 70 of a shaft and a bearing of the machine;

Fig. 5 is a sectional view taken on the line V-V of Fig. 6; and

Fig. 6 is a sectional view taken on the line VI-VI of Fig. 2 showing the form of a 75 dust receiving member of the machine.

Upon a frame or standard 10 (Figs. 1 and 2) is mounted a housing 12 which carries all of the operative instrumentalities 80 of the machine. A shaft 16 journalled in the housing 12 extends transversely of the standard 10 and carries at each end a scouring wheel 18. A spiral gear 20 is keyed upon the shaft 16 at the center thereof, and meshing with the gear 20 is a second spiral gear 22 keyed upon the forward end of a rearwardly extending drive shaft 24 which is journalled in a bearing block 26 (Fig. 3) fitted within the housing 12 and retained therein by a set screw 25. The housing 12 encloses the gears 20 and 22 and thus constitutes a gear casing. A circular opening 85 is provided in the front wall of the housing 12 to permit access to the bearing block 26 and the gear 22 for removing or replacing these members, and this opening is closed by a circular cover 27 (Fig. 2) which is threaded into the housing 12 and which is provided with a pair of aligned slotted lugs 29 into which a tool may be inserted for 90 95 100

turning the cover 27. In Fig. 2, one of the lugs 29 conceals the other. In Fig. 1 the machine is shown with the cover 27 removed. Upon the rear end of the shaft 24 is mounted a coupling member 28 through which a motor 30 drives the shaft 24. A cover 14 secured to the housing 12 encloses the coupling 28. The motor 30 is bolted upon a table 32 (Fig. 2) which has a stem portion 34 vertically adjustable in a rearward extension 36 of the housing 12. An adjusting screw 38 is threaded in the table 32 and bears against the extension 36, thereby determining the height of the table 32. A set screw 40 threaded in the extension 36 bears against the stem 34 and thus holds the table 32 in adjusted position. A switch 42 mounted upon the front of the standard 10 controls the rotation of the scouring wheels 18 through the starting and stopping of the motor 30.

The speed of rotation of the scouring wheels 18 depends upon the size of the gear 22. If a faster speed is desired, the gear 22 is removed and a larger gear 22 of the same character is substituted therefor, while if a slower speed is desired, a smaller gear 22 is substituted therefor. The level of the shaft 24 depends upon the pitch diameter of the gear 22; and to accommodate the varying levels of the shaft 24 a series of bearing blocks 26 are provided, all of which bearing blocks have the same external dimensions so as to fit within the housing 12, but having bores at varying levels for the shaft 24. In the illustrated machine each of the blocks 26 is cylindrical, and is provided with a keyway 44 which cooperates with a pin 46 secured in the housing 12 to determine the position of the block 26 before securing the latter by the set screw 25 and thus to center the shaft 24. As the shaft 24 is raised or lowered by substituting the various blocks 26, the motor 30 may be raised or lowered 45 into alignment with the shaft 24 by means of the adjusting device previously described.

An oil well 48 (Fig. 1) is formed in the housing 12 and contains oil for lubricating the gears 20 and 22 and the shaft 24. A chain 50 running over a collar 52 on the shaft 24 raises oil from the well 48 and communicates it directly to the gear 22. Some oil is spattered from the chain 50 and the gear 22 upon the upper wall of the housing 12 and this spattered oil runs down a rib 54 formed in the upper wall of the housing 12 and is conducted to a passage 56 (Fig. 3) communicating with one end of a longitudinal oil groove 58 in the bearing block 26 to lubricate the shaft 24. A passage 60 at the opposite end of the block 26, communicating with a passage 62 in the housing 12, drains off any surplus oil which collects in an annular recess 64 in the end of the block 26 and conducts it to the well 48.

A bushing member 66 (Fig. 1) is disposed upon either side of the gear 20, the bushing members 66 being secured to the housing 12 to provide bearings for the shaft 16. A recess in the form of a longitudinal oil groove 68 (Fig. 4) is formed in each of the bushings 66 for lubricating the shaft 16, and is supplied by an oil cup 70 (Fig. 1). An annular recess 72 (Fig. 4) is formed in each bushing 66 adjacent to the outer end thereof and beyond the end of the oil groove 68 to collect surplus oil, and a passage 74 in each bushing 66 drains the surplus oil from each recess 72 and conducts it to the well 48. A plurality of annular grooves 76 are formed 80 in the portions of the shaft 16 which rotate within the recesses 72, the grooves 76 being adjacent to each other and thereby providing a series of sharp crests or ridges between them. Most of the surplus oil which travels outwardly along the shaft 16 will be whirled off the ridge between the inmost groove 76 and the adjacent groove and will run down the wall of the recess 72 and drain out through the passage 74. Any oil not thus disposed of will ordinarily be whirled off the second ridge, and the following ridges will serve to take care of any unusual surplus of oil. A thrust collar 78 is secured to shaft 16 in a position to bear against the outer ends respectively of the bushings 66; and a groove is formed on each of the collars 78 to provide a beveled edge 80 adjacent to the outer ends respectively of the bushings 66. In case any slight amount of oil 100 should escape from the bushings 66 it will be caught upon the beveled edges 80 and whirled upon the interior wall of an annular overhanging portion 82 formed on each of the bushings 66, and will thus be prevented 105 from spattering into the room.

For collecting the dust given off by the work during the scouring of the heels, a draft conduit 84 is provided for each of the scouring wheels 18. The conduits 84 are 110 each connected at one end 86 to a main suction conduit 88 such as is ordinarily provided to carry away the dust from scouring machines. The openings of the main conduit 88 to which the conduits 84 are connected constitute the usual intake openings of a suction draft system. Each conduit 84 is supported by a rod 90 (Figs. 1 and 2) which is secured by a set screw 92 to a depending flange 94 of the head 12. A flange 96 on the conduit 84 is secured to the rod 90 by a second set screw 98. Further support for each conduit 84 is provided by a second rod 100, which is secured to the head 12 by a set screw 102. A flange 104 on the conduit 84 is secured to the rod 100 by a second set screw 106. The conduits 84 are both alike, and a description of one will suffice. The lower end 125 86 of the conduit 84 is substantially cylindri- 130

cal to conform to the usual shape of the receiving end of the main conduit 84. From its lower end 86 the conduit 84 (Fig. 2) extends forwardly and upwardly, with its axis inclined at substantially 45° to the horizontal and substantially tangent to the scouring wheel 18 at the forward portion of the periphery of the latter. The cross section of the conduit 84 gradually changes, upon approaching its upper end, from circular to rectangular form, the corners of the rectangle being well rounded.

A partition 108 divides the upper portion of the conduit 84 into a forward and a rearward passage 110 and 112, respectively. The upper end of the partition 108 extends in a plane substantially radial to the scouring wheel 18 and terminates as closely to the periphery of the wheel 18 as possible, allowing reasonable clearance. The lower end of the partition 108 extends in a plane substantially parallel to the above-mentioned axis of the conduit 84 and is so spaced as to provide a ratio of substantially 5 to 4 between the cross-sectional areas of the forward and rearward passages which it forms in the conduit 84. The intermediate portion of the partition 108 curves smoothly from the one to the other of the above-mentioned planes.

The forward upper portion of the conduit 84, now to be described, is so shaped as to enable the forward passage 110 to gather all of the dust whirled away from the wheel 18, while allowing full freedom of manipulation of a shoe S as the operator presents the heel of the shoe S to the wheel 18. The sides of the conduit 84 are therefore coned outwardly and upwardly (Figs. 1, 2, 5 and 6) to form lateral bulges 114 in the passage 110, the vertices of the approximate cones being truncated by the adjacent unbulged portions of the sides of the conduit 84. The walls of the two bulged portions 114 terminate in edges 115 which lie in a plane perpendicular to the plane of the upper portion of the partition 108 and parallel to the axis of the wheel 18 and which intersects the upper portion of the partition 108 at a point close to the upper end thereof. The walls of the bulges 114 do not come together in front but the forward upper portion of each wall is flared outwardly and forwardly, curving smoothly into a wall 116 which is substantially flat. The two walls 116 together form a V-shaped trough, the vertex of which extends forwardly and downwardly, and the bottom of which is open, the bottom of this trough communicating with the passage 110 by a passage formed between a pair of flat walls 118. The walls 118 curve smoothly into the walls 116 respectively and into the forward wall of the conduit 84, diverging as they approach the forward wall of the conduit 84.

The upper or inner end of the trough be-

tween the walls 116 communicates directly with the interior of the space within the bulges 114. The lower or outer end of this trough is closed by a wall 120 which also closes the bottom of the passage between the walls 118, the outer end portion of the wall 120 being flat and the inner end portion curving smoothly into the forward portion of the wall of the conduit 84 at a point above the lower end of the partition 108 and below the beginning of the bulged portions 114. The flat portion of the wall 120 slopes forwardly and downwardly at a small inclination to the horizontal. Each of the walls 116 of the trough has an upper or forward edge 122 which is continuous with one of the edges 115, but the edges 122 slope forwardly and downwardly at a much steeper angle than the edges 116. Because of the curvature between the walls 116 of the trough and the walls 118 of the passage with which the bottom of the trough communicates, the bottom of the trough is not clearly defined. It is represented, however, in Figs. 1 and 6 by the lines 124, which are lines of tangency seen by an observer looking horizontally into the trough; and it is also represented by the shade lines 124 in Figs. 2 and 5. The entire conduit 84 is symmetrical with respect to the mid-plane of the wheel 18, and the above-described trough therefore may be described in the commonly employed term as "lying in the plane of the wheel".

The walls of the passage 112 terminate at the upper end of the partition 108 and are flanged outwardly as at 126 (Fig. 2), the lower surface of the flange 126 lying substantially in the plane of the edges 115. A hood 128 partly encloses the rear portion of the wheel 18 and communicates at its lower end with the passage 112. The hood 128 is pivoted at 130 to the flange 104 of the conduit 84, and is provided with an external flange 132 which rests upon the flange 126. The rear wall of the hood 128, as shown in Fig. 2 is approximately spiral with respect to the axis of the wheel 18, gradually approaching the periphery of the wheel 18 up to a point slightly forward of the top-most portion of the wheel 18, at which point it is spaced from the periphery of the wheel 18 only by a convenient clearance. The sides of the hood 128 partly cover the sides of the rear portion of the wheel 18, being spaced therefrom only by a convenient clearance. The hood 128 thus encloses the periphery and partly encloses the side walls of the wheel 18 over a large sector, substantially 180° , of the wheel 18. The shape of the hood 128 as above described, conforms to the natural stream lines of the air passing through it, since no portion of the hood 128 extends cross-wise with respect to these stream lines, and since there are no re-entrant or constricted portions or any sudden

130

changes of direction in the hood 128 which might cause eddy currents or dead air spaces, or which might otherwise break up the natural stream lines. The hood 128 therefore provides a stream-line passage around the sector of the wheel 18 which it partially encloses. In the design of the conduit 84, all portions of the passage 112 are given a cross-sectional area at least as great as the area across the natural stream lines of the current of air flowing between the wheel 18 and any portion of the hood 128, so as not to choke the draft through the hood.

In operation, the switch 42 is turned on, starting the motor 30. The direction of rotation of the motor 30 is such as to cause the wheels 18 to rotate in a clockwise direction as viewed in Fig. 2; that is, the forward portion of the periphery of each wheel 18 moves downward. As the edge of the heel of the shoe S is presented to the periphery of the scouring wheel 18, dust will be given off. It will be noted that the two bulged portions 114 of the passage 110 together with the upper portion of the partition 108 constitute a funnel-like structure having its large open end adjacent to the periphery of the wheel 18, and which will be hereafter termed a "funnel", although the forward wall of this funnel is not closed but opens directly into the trough formed by the walls 116. Most of the above-mentioned dust consists of a cloud of minute particles and will be received directly into the funnel and then carried down the passage 110 by the draft in the conduits 88 and 84. Many of the larger particles of dust as well as some of the fine dust cloud above mentioned, will be projected downwardly at too steep an angle to enter the funnel, and this portion of the dust will be received in the trough between the sloping walls 116, and will be carried by the above-mentioned draft through the passage 110 between the walls 118 and thence down the passage 110. The bulged portions 114 and the sloping walls 116 provide an open dust receiving end for the passage 110 of such size and shape as to gather in substantially all of the dust thrown away from the wheel 18. Because the coned walls of the portions 114 and the sloping walls 116 converge inwardly, they serve to accelerate the air current passing through them and thus to ensure that the entrained dust particles will be carried along by the current and will not settle upon any of the walls. Furthermore, the bottom of the trough indicated by the lines 124, is so positioned that the shoe S may be manipulated in any necessary manner without the walls 116 interfering with the toe portion of the shoe. The wall 120 which closes the lower forward end of the trough is inclined upwardly as it extends rearwardly in order to contract the area

through which the air current passes, and thus to accelerate the current.

The wheel 18, because of its rapid rotation, will tend to set up a current of its own and carry a whirl of the lighter dust around with it. This tendency is overcome, however, by two features of the above-described dust collecting agencies. The first of these features is the partition 108, which extends radially of the wheel 18 as close as may be, allowing for reasonable clearance, to the periphery thereof, and thus directly cuts off most of the peripheral current and directs most of the dust entrained in the peripheral current into the funnel. The second feature consists of the hood 128, which is connected to the suction system through the passage 112; and since the partition 108 extends down the conduit 84 to a point below where the cross-sectional area of the conduit 84 begins to widen, the passage 112 will communicate the full intensity of the suction system to the hood 128 regardless of any widening in the cross-sectional area of the passage 110. The hood 128 will therefore maintain a counter current of air half way around the wheel 18; opposing any tendency of the wheel 18 to set up a circular current in the direction of its rotation. The spiral form of the hood 128 enables it to accommodate the volume of air drawn in through the clearance spaces between the walls of the hood and the sides of the wheel 18 and at the same time to maintain the full intensity of the suction all the way to the top forward end of the hood, so that even at that point the tendency of the wheel to create a peripheral current will be overcome and there will be a draft leading into the hood.

Having thus described my invention what I claim as new and desire to secure by Letters Patent of the United States is:

1. In an abrading machine, an abrading wheel, and a dust collecting member having a portion in the form of a funnel having its large open end adjacent to the periphery of said wheel to receive dust from the work, another portion of said dust collecting member being in the form of an open-bottomed V-shaped trough lying in the plane of said wheel and opening at one end into said funnel through the wall of said funnel to receive additional dust from the work, the opposite end of said trough being closed and being below the level of the first-mentioned end, and the remaining portion of said dust collecting member being in the form of a conduit providing communication between the intake of a suction draft system and the small end of said funnel, said conduit also providing communication between the suction draft system and the bottom of said trough.

2. In a heel scouring machine, a scouring wheel, and a conduit comprising a draft pas-

sage and having one end adapted to be connected to the intake of a suction draft system, the opposite end of said conduit comprising a funnel having its large open end 5 adjacent to the periphery of said wheel to receive dust from the work, an open-bottomed V-shaped trough constructed and arranged to receive additional dust from the work and to accommodate the toe portion of

10

a shoe as the shoe is manipulated to present the edge of the heel thereof to the periphery of said wheel, one end of said trough opening into said funnel through the wall of said funnel, a closure for the opposite end of said trough, and a passage connecting the bottom of said trough with the intermediate portion of said conduit.
